Primary Examiner — Mary Ann Calabrese
Assistant Examiner — Jennifer L Rempfer(57) **CLAIM**

The ornamental design for an infant towel drying mat, as shown and described.

DESCRIPTION

FIG. 1 is a perspective view of an infant towel drying rack in an unfolded position;

FIG. 2 is a front elevational view thereof, the rear being a mirror image;

FIG. 3 is a right side elevational view thereof, the left side being a mirror image;

FIG. 4 is a top plan view thereof; and

FIG. 5 is a bottom plan view thereof.

FIG. 6 is a perspective view of an infant towel drying rack in a partially folded position;

FIG. 7 is a front elevational view thereof;

FIG. 8 is a rear elevational view thereof;

FIG. 9 is a right side elevational view thereof, the left side being a mirror image;

FIG. 10 is a top plan view thereof; and

FIG. 11 is a bottom plan view thereof.

FIG. 12 is a perspective view of an infant towel drying rack in a fully folded position;

FIG. 13 is a front elevational view thereof;

FIG. 14 is a rear elevational view thereof;

FIG. 15 is a right side elevational view thereof, the left side being a mirror image; and,

FIG. 16 is a top plan view thereof, the bottom being a mirror image.
